UNITED STATES PATENT OFFICE

171,097

PIANO CASE

William Millington, Grand Rapids, Mich., and
Wilbur M. Day, Kenwood, Ohio, assignors to
The Baldwin Company, Cincinnati, Ohio, a cor-
poration of Ohio

Application February 5, 1953, Serial No. 23,455

Term of patent 14 years

(Cl. D56—9)

To all whom it may concern:

Be it known that we, William Millington and Wilbur M. Day, have invented a new, original, and ornamental Design for a Piano Case, of which the following is a specification, reference being had to the accompanying drawing, forming a part hereof.

Fig. 1 is a perspective view of a piano case showing our new design.

Fig. 2 is an enlarged sectional view taken on the line 2—2 of Fig. 1.

Fig. 3 is an enlarged sectional view taken on the line 3—3 of Fig. 1.

We claim:

The ornamental design for a piano case, sub-
stantially as shown.

WILLIAM MILLINGTON.
WILBUR M. DAY.
